[57] CLAIM

The ornamental design for a cap for pipe, as shown and described.

DESCRIPTION

FIG. 1 is a perspective view of a cap for pipe showing my new design;

FIG. 2 is a top view thereof;

FIG. 3 is a bottom view thereof;

FIG. 4 is a side elevational view thereof, the opposite side being a mirror image; and,

FIG. 5 is a front view thereof, the rear view being a mirror image.

The fishing line and cylinder shown in broken lines in FIG. 1 are for illustrative purposes only and form no part of the claimed design.
